Primary Examiner — Kevin K Rudzinski*Assistant Examiner* — James P Mckane(74) *Attorney, Agent, or Firm* — Sanchelima & Associates, P.A.; Jesus Sanchelima; Christian Sanchelima(57) **CLAIM**

The ornamental design for a shower cap wrap as shown and described.

DESCRIPTION

FIG. 1 is a perspective view of a shower cap wrap showing my new design;

FIG. 2 is a front elevational view thereof;

FIG. 3 is a rear elevational view thereof;

FIG. 4 is a left side elevational view thereof;

FIG. 5 is a right side elevational view thereof.

FIG. 6 is a top plan view thereof;

FIG. 7 is a bottom plan view thereof; and,

FIG. 8 is a perspective view thereof.

The broken lines in the drawings illustrate portions of the shower cap wrap which form no part of the claimed design.

1 Claim, 5 Drawing Sheets
